UNITED STATES PATENT OFFICE.

WILLIAM J. BURROW, OF PLYMOUTH, MICHIGAN, ASSIGNOR TO THE DAISY
MANUFACTURING COMPANY, OF SAME PLACE.

AIR-RIFLE.

SPECIFICATION forming part of Letters Patent No. 660,070, dated October 16, 1900.

Application filed January 4, 1900. Serial No. 300. (No model.)

To all whom it may concern:

Be it known that I, WILLIAM J. BURROW, a citizen of the United States, residing at Plymouth, in the county of Wayne and State of Michigan, have invented certain new and useful Improvements in Air-Rifles; and I do declare the following to be a full, clear, and exact description of the invention, such as will enable others skilled in the art to which it applies to make and use the same, reference being had to the accompanying drawings, and to the figures of reference marked thereon, which form a part of this specification.

This invention relates to air-guns of the breakdown pattern; and it consists in the construction and arrangement of parts hereinafter fully set forth, and pointed out particularly in the claims.

The object of the invention is to produce an air-gun of the class described in which the arrangement is such as to provide for attaching the rear end of the false barrel to the pivoted extension of the stock in a simple and permanent manner, so that said stock extension shall lie within and form a complementary portion of the false barrel at its rear end and at the same time afford a shoulder against which the spring which projects the piston may be compressed, and to provide a lock at the rear end of the false barrel which serves to retain said barrel in position upon said extension of the stock.

The above object is attained by the formation and association of parts illustrated in the accompanying drawings, in which—

Figure 1 is a general view, in side elevation, of an air-gun embodying my invention. Fig. 2 is an enlarged detail, in side elevation, of a portion of the stock and its pivoted extension, together with the spring for projecting the piston and the piston-rod passing therethrough. Fig. 3 is an enlarged transverse section as on line 3 3 of Fig. 1. Fig. 4 is a horizontal section through the rear end of the false barrel, showing the pivoted extension of the stock in plan lying therein. Fig. 5 is an inverted plan of the forward end of the extension of the stock and the rear end of the false barrel, showing the opening in the under side of said barrel adapted to be filled and closed by the extension of the stock.

Fig. 6 is a detail in perspective of the rear end of the pivoted extension of the stock, other parts being broken away, said figure showing the recess or channel therein which receives the curved reinforcing-plate attached to the inner wall of the rear end of the false barrel.

Referring to the characters of reference, 1 designates the false barrel, shaped to form an air-chamber 2 therein at its rear end and having in its forward end a true barrel (not shown) adapted to convey the projectile in a manner common and well known in the art. Passing rearwardly through the air-chamber 2 is a piston-rod 3, carrying at its forward end a piston (not shown) adapted to reciprocate within the air-chamber and create sufficient pressure therein to expel the projectile from the true barrel of the gun in a manner well understood. Surrounding the piston-rod 3 is a coiled spring 4, whose forward end engages the piston.

The false barrel 1 at its rear end is open on its under face, as shown at 5 in Fig. 5.

The stock 6 is provided with the opposed side plates 7, between which the extension 8 of the stock is pivoted, as at 9. Said pivoted extension of the stock is provided with a forwardly-projecting under portion 10, adapted to lie within and fill the opening 5 in the under face of the false barrel and having at its forward end a groove or channel 11, (see Fig. 2,) adapted to receive the wall of said barrel at the forward end of said opening, so as to securely lock the extension 10 of the stock at its forward end to the false barrel. The pivoted extension of the stock carries the trigger-guard 12 and the trigger 13. Formed in the extension 8 of the stock at the point of termination of the rear end of the false barrel is a recess or channel 14, which occupies the opposite sides of said extension and extends in a curved line across the top thereof, so as to conform to the shape of the false barrel. Secured within the rear end of the barrel 1 is a curved reinforcing-plate 15, which stands in relief from the inner wall of said barrel and is adapted to lie within the recess or channel 14 of the stock extension, the forward edge of said reinforcing-plate engaging the forward shoulder or margin 16 of said re-

cess, thereby firmly holding the false barrel in place against the forward longitudinal thrust exerted by the piston when driven by the spring 4 in the act of discharging the gun.

- 5 To secure the rear end of the false barrel properly in place on the stock extension 8, a screw 17 is passed through said parts, as clearly shown in Fig. 3.

To the plates 7 of the stock is pivoted at 10 the rear end of a link 19, whose forward end engages the hook 20 on the rear end of the piston-rod. Upon the forward end of the stock extension, within the barrel, is a vertical shoulder 21, against which the rear end 15 of the spring 4 bears. By breaking down the barrel, as shown by dotted lines in Fig. 2, the link 19 draws the piston-rod rearwardly, so as to compress the spring 4 between the piston and the shoulder 21 of the stock extension, 20 at the same time causing the hook 20 of the piston-rod to be engaged and retained by the trigger 13. The barrel is then thrown back to the locked position and the gun is ready for firing, the piston being discharged by drawing upon the trigger, so as to disengage it from 25 the hook of the piston-rod.

Having thus fully set forth my invention, what I claim as new, and desire to secure by Letters Patent, is—

- 30 1. In an air-gun, the combination of the stock, the stock extension pivoted thereto and having a forwardly-projecting portion, the false barrel having an opening in its under side at its rear end, said extension of the stock 35 lying in and closing said opening, the forward end of said extension having means for en-

gagement with the wall of said barrel on its under side so as to lock said parts when forced together.

2. In an air-gun, the combination of the 40 stock, the stock extension pivoted thereto, the false barrel adapted to embrace the upper portion of said extension of the stock and having an opening in its under wall, said extension lying in an opening in the under side of 45 said barrel and forming a complementary portion of the wall thereof, a shoulder upon the rear end of said extension and a projection upon the inner face of the barrel, adapted to engage said shoulder. 50

3. In an air-gun, the combination of the stock having side plates, the extension of the stock pivoted between said plates, the barrel mounted upon said extension, a recess formed in the rear end of the extension and a reinforcing-plate upon the inner wall of the rear end of the barrel adapted to lie in said recess. 55

4. In an air-gun, the combination of the stock, the stock extension pivoted thereto, said extension having at its forward end 60 means for attachment to the barrel and having a vertical shoulder projecting within the barrel, the piston-projecting spring having its rear end bearing against said shoulder and means for compressing and releasing said 65 spring.

In testimony whereof I sign this specification in the presence of two witnesses.

WILLIAM J. BURROW.
